ABSTRACT

A load lifting mechanism for lift trucks in which an extensible mast carries a cantilever type load lifting carriage and is vertically actuated by a hydraulic ram and associated load lifting chains. The bending moment created by the load carried on the carriage is counterbalanced by a bending moment derived from load lifting tension elements acting on counterbalancing arms attached to an upper section of the mast, thereby substantially reducing or eliminating bending stresses on the mast regardless of the size of the load being lifted. A pair of laterally spaced chains are utilized as the tension elements in conjunction with laterally spaced counterbalancing arms and similarly spaced chain orienting arms connected to a lower section of the mast and/or to truck anchor points so that lateral as well as fore and aft stability of the mast and associated lift truck is increased. Preferably, the mast is oriented in a fixed upright position relative to the lift truck and a tilting carriage as disclosed herein is used for tilting the forks or other load lifting device attached to the carriage. Several embodiments of counterbalanced masts and telescoping dual rail mast sections and lift chain reeving arrangements are also disclosed.

LIFT TRUCK LOAD LIFTING MECHANISM

This application is a continuation of my copending parent application Ser. No. 660,630, filed Aug. 15, 1967 and titled "Lift Truck Load Lifting Mechanism," now abandoned in favor of this continuation application.

An object of the present invention is to provide an improved load lifting mechanism for industrial and/or off-the-road lift trucks of the type having an extensible load lifting mast and associated load lifting chains actuated by a hydraulic ram to lift a load supported in cantilever fashion on a carriage of the mast wherein load-induced bending stresses are counterbalanced by forces transmitted in tension through the load lifting chains to thereby provide, in conjunction with other features of the invention, a load lifting mechanism which results in: (1) an economical and lightweight construction which is efficient and reliable in operation, (2) less strain on the mast parts and truck frame and axle, (3) an increased load lifting capacity, (4) greater stability, (5) lower center of gravity, (6) less power to raise the load, (7) faster lift speed, (8) a smaller oil reservoir in the hydraulic supply system, (9) adaptability to a variety of existing truck designs, (10) a greater range of load lifting capacities for a given design of truck and mast, (11) greater off-center load ratings both fore and aft and side to side, (12) a greater margin of safety to the operator as well as the equipment and (13) improved visibility.

Another object is to provide an improved tilting carriage mechanism for lift truck masts which pivots the load carried on the carriage substantially about the center of gravity of the load, thereby reducing the power required to actuate the tilting carriage, and which minimizes the space and structural requirements of the carriage.

A further object is to provide an improved lift truck equipped with a counterbalanced load lifting mechanism of the aforementioned character which cooperates with an overhead guard for the operator of the truck to provide improved protection for the operator and better support for the mast while reducing the stresses imposed by the mast on the truck frame.

Other objects as well as the features and advantages of the present invention will become apparent from the following detailed description taken in conjunction with the accompanying drawings wherein:

FIG. 1 is a side elevational view of an extensible load lifting mechanism and lift truck constructed in accordance with the present invention with the carriage and mast thereof shown in full lift position.

FIGS. 2, 3, 4, and 5 are simplified semi-schematic vertical center sectional views respectively showing the mast of FIG. 1 in fully extended position (FIG. 2), about half-way extended (FIG. 3), slightly extended with the carriage at the upper limit of the free lift range of the mast (FIG. 4), and with the mast fully collapsed and the carriage at ground level (FIG. 5).

FIG. 6 is a fragmentary side elevational view of the mast structure of FIG. 1 with the mast in its fully collapsed condition corresponding to FIG. 5.

FIG. 7 is a fragmentary vertical section taken on the line 7-7 of FIG. 6.

FIG. 8 is a fragmentary side elevational view of the mast of FIG. 1 shown in the position of FIG. 3 and with portions broken away to illustrate detail.

FIG. 9 is a top plan view of the mast of FIG. 1.

FIG. 10 is a horizontal section taken on the line 10-10 of FIG. 1.

FIG. 11 is a fragmentary side elevational view of the mast of FIG. 1 with the ram and mast sections shown in telescoped collapsed condition of FIG. 5 but with the carriage and counterbalancing arms removed for clarity.

FIG. 12 is a fragmentary horizontal section taken on line 12-12 of FIG. 11.

FIG. 13 is the fragmentary side elevational view of the mast of FIG. 1 shown in the partially extended condition of FIG. 4 with the carriage and counterbalancing arms removed and portions broken away to better illustrate detail.

FIG. 14 is a fragmentary vertical center sectional view taken on the line 14-14 of FIG. 9 illustrating on an enlarged scale the hydraulic ram of the load lifting mechanism in fully extended condition.

FIG. 15 is a vertical sectional view of the ram similar to that of FIG. 14 but showing the ram in its fully collapsed or telescoped condition.

FIGS. 16, 17, and 18 are horizontal sectional views taken respectively on the lines 16-16, 17-17, and 18-18 of FIG. 14.

FIG. 19 is a fragmentary front elevational view of the lower portion of the mast in collapsed condition illustrating the load lifting carriage of the invention.

FIG. 20 is a fragmentary side elevational view of the carriage and mast structure shown in FIG. 19 but on a larger scale.

FIG. 21 is a horizontal section taken on the line 21-21 of FIG. 20.

FIG. 22 is a fragmentary side elevational view of the structure shown in FIG. 20 illustrating by solid lines and in phantom line positions the range of tilting movement of the carriage.

FIG. 23 is a fragmentary perspective semi-schematic view of a second embodiment of a lift mast employing the ram of the first embodiment of FIGS. 1-22 and a similar chain rigging arrangement applied to a non-counterbalanced four section mast.

FIGS. 24 and 25 are semi-schematic fragmentary perspective views of third and fourth embodiments respectively of extensible lift truck masts in accordance with the present invention.

FIGS. 26, 27, and 28 are semi-schematic side elevational views of the second, third and fourth mast embodiment shown respectively in FIGS. 23, 24, and 25 in their respective full-lift positions.

INTRODUCTION

The principles of the present invention are applicable to load lifting mechanisms incorporating an extensible framework, commonly termed a "mast," made up of one or more "sections," depending upon the load lifting capacity and vertical load lifting range desired. The term "mast section" refers usually to a rectangular framework made up generally of a pair of horizontally spaced and vertically extending "rails" suitably interconnected by horizontal braces and adapted to telescopically interengage with the rails of another such section of the mast. The term "rails" refers to the vertical side members of a mast section, which may be mill-formed beam sections, and which are commonly used in pairs in lift mast constructions as the uprights of a mast section. The term "ram" as used herein refers to

the hydraulically operated piston and cylinder unit employed to impart vertical movement to the load lifting mechanism, and preferably comprises a simple two-part ram made up of a cylinder which constitutes the external member of the ram and an internal plunger which telescopes within the cylinder. However, other known multi-part ram constructions may be employed if desired, as will become apparent hereinafter. The term "carriage" refers to the apron which travels vertically on the uppermost section of the mast and the forks or other associated cantilevered attachment which directly carries the cargo or load to be raised, lowered and/or transported. The term "chain" refers to the usual flexible load supporting elements which transmit tension loading and operatively interconnect the ram, mast sections and carriage. These elements preferably comprise the well known link and roller type chains since they operate with a minimum of friction and stretch, but other types of chains, cables, belts or equivalent elements may be employed if their "stretch factor" is suitably taken into account.

"FOUR-RAIL CAPACITY" MAST 30

The first embodiment of a load lifting mechanism constructed in accordance with the present invention is illustrated in FIGS. 1-22 inclusive and comprises a two-section mast 30 having the lifting range of a conventional "four-rail" mast. Referring to FIG. 1, mast 30 is shown extended to its full height and mounted in fixed vertical position on a lift truck 32 which may be of the off-the-road type shown or a hard tire industrial type. Despite its high lift range and low collapsed clearance, mast 30 has only two sections, a lower, dual rail section 34 supported near its lower end on the front pin 36 of truck 32, and rigidly connected at its upper end to the rear of truck 32 by an overhead framework 38 which also serves as a safety guard for the operator of the truck. The other, upper section 40 of mast 30 is vertically moveable and slideably telescopes along the outer sides of section 34 when the two sections overlap in the lower lifting range of the mast. Mast 30 is equipped with a load lifting carriage 42 which tracks on section 40, with a two-part ram 44, and with two sets of lift chains 58, 58' and 62, 62'.

Further details of the structure and operation of mast 30 will become apparent from the detailed description of the mast structure as shown in FIGS. 6-22 inclusive. However, it is believed that prefacing such description with an explanation of the structural organization and operating principles of the principal components of mast 30 as shown semi-schematically in FIGS. 2-5 inclusive will better facilitate an understanding of the invention. In these semi-schematic views section 40 is shown spaced horizontally out in front or forward of section 34 in order to permit clearer illustration of the chain reaving arrangement, it being understood that in practice section 40 embraces section 34 and thus is vertically aligned therewith as shown in FIGS. 1 and 6-13. Also, FIGS. 2-5 inclusive show only the right-hand components (as viewed by the truck operator) of the mast sections and chain rigging. Since much of the mast structure is symmetrical, the left-hand components are generally duplicates of the right-hand components and their reference numerals have been given a prime mark "'' suffix to indicate this relationship.

Referring to FIGS. 2-5 inclusive, carriage 42 has a pair of vertically spaced rollers 46 and 48 linked to an apron 50 of the carriage by a tilting mechanism described hereinafter in conjunction with FIGS. 19-22. 5 Rollers 46, 48 track in the outwardly facing channel or groove 52 defined by the channel-shaped rail 54 of section 40 to thereby guide vertical travel of carriage 42 on section 40 and to provide cantilever support for the apron throughout such travel. A single hydraulic ram 10 44 is interposed structurally and functionally between sections 34 and 40 to vertically extend mast 30 and to elevate carriage 42 on section 40. Preferably, the lower member of ram 44 is an external cylinder 56 suspended for vertical movement by a first pair of laterally spaced chains 58, 58' from section 34, and the upper member 15 constitutes the ram plunger which is a cylinder-type piston 60 telescopically received in the upper end of cylinder 56. The upper mast section 40 is suspended on plunger 60 by a second pair of laterally spaced chains 62, 62'.

A first pair of counterbalancing arms 64, 64' are rigidly fixed to the upper end of section 40 and extend rearwardly therefrom in outwardly diverging relation to 25 one another on the opposite side of the mast from the forwardly extending forks 66 of carriage 42. A second pair of arms 68, 68' are rigidly fixed to the upper end of section 34 and are oriented in the same manner as arms 64, 64'. A sheave 70 is rotatably supported by arm 64 30 at the outer end thereof and another sheave 72 is rotatably supported near the fixed end of arm 64 to guide chain 58 along the vertical path of travel of apron 50. Lower arm 68 also rotatably carries two chain sheaves 74 and 76, sheave 74 being vertically aligned 35 with sheave 70 near the outer end of arm 68 and sheave 76 being mounted near the junction of arm 68 and section 34. A pair of sheaves 78, 78' are journaled on the lower end of ram 44, one on each side of cylinder 56, and another pair of sheaves 80, 80' are journaled on the upper end of plunger 60. Chains 58, 58' are each fixed at one end respectively by connections 86, 86' to the upper end of section 34 and have runs 116, 116' extending downwardly therefrom to sheaves 78, 71' respectively, thence are trained around sheaves 78, 78', and have runs 114, 114' extending vertically up to sheaves 76, 76' respectively. Chains 58, 58' then run out to and under sheaves 74, 74', then upwardly in a vertical run 112, 112' to and over sheaves 70, 70', then 40 horizontally to and over the respective sheaves 72, 72', and finally downwardly in vertical runs 113, 113' to connection 88, 88' with the uprights of apron 50.

The second pair of chains 62, 62' are fixed at one end 82, 82' to the lower end of section 40 and then extend upwardly in vertical runs 63, 63' over sheaves 80, 80' respectively and then downwardly in vertical runs 55 65, 65' to connections 84, 84' with the upper end of cylinder 56.

Cylinder 56 is guided for vertical movement relative 60 to section 34 by three horizontally spaced rollers 90, 92 and 94 (see also FIG. 10) preferably journaled on the upper end of section 34 at 120 degree angular intervals for rolling engagement with the outer surface of cylinder 56. A pair of guide rollers 96, 96' are rotatably mounted on the lower end of ram 44 below sheaves 78, 78', one on each side of cylinder 56, and respectively 65 track in the inwardly facing channel grooves 98, 98'

respectively of rails 35, 35' of section 34 to guide cylinder 56 for vertical movement between these rails.

Section 40 is slideably guided for vertical movement during the first portion of its upward travel by being telescopically received on lower mast section 34, i.e., the flat inner sides of rails 54, 54' can slide against the flat outer sides of rails 35, 35' respectively, and a guide plate 100 (FIGS. 1 and 8) extending across the front of section 40 slides along the forward edges of rails 35, 35' during the portion of the travel of section 40 in which it overlaps section 34. However, after being lifted clear of section 34, section 40 is vertically guided solely by a guide bracket 102 rigidly connected to the upper end of plunger 60. Bracket 102 slideably embraces rails 54, 54' of section 40 throughout its range of vertical travel between the fully extended "full lift" position of the mast shown in FIG. 2 and the fully collapsed or "completely retracted" position of the mast shown in FIG. 5. As a supplement or alternative to bracket 102, a guide tube (not shown) may be telescopically and non-rotatably mounted within plunger 60 and fixed at its upper end to section 40.

It is to be noted that bracket 102 prevents section 40 from twisting or rotating relative to plunger 60, and that carriage rollers 46, 48, and 46', 48' tracking in spaced rails 54, 54' prevent twisting of carriage 42 relative to section 40. Plunger 60 is also slideably keyed against rotation relative to cylinder 56 by a pair of axially extending keys 104 and 106 which are fixed diametrically opposite one another (FIG. 2) to the inner wall of cylinder 56. Keys 104, 106 slideably fit in axially extending grooves in a sleeve 108 fixed to the lower end of plunger 60. This ram-mast section guiding and keying arrangement prevents rotation of section 40 relative to section 34 about the vertical axis of mast 30, an essential feature particularly when sections 40 and 34 are separated from one another during the upper portion of the lifting sequence of mast 30. The plunger-cylinder keying structure also serves as the principal slide bearing between plunger 60 and cylinder 56, thereby obviating the need for machining the bore of cylinder 56 and thus considerably reducing the cost of manufacturing ram 44.

OPERATION OF MAST 30

The load lifting sequence of operation of mast 30 through its full range begins with the mast in the fully retracted position shown in FIG. 5 and progresses through the stages shown sequentially in FIGS. 4, 3, 2 in that order. Hydraulic fluid is admitted to the lower end of cylinder 56 via hose line 110 from a suitable pressure source, such as the usual hydraulic pump on truck 32, under the control of the truck operator to thereby drive plunger 60 upwardly in cylinder 56 and thus vertically extend ram 44. Cylinder 56 can not move downwardly since it is suspended in the bight of chains 58, 58' which are carrying the weight of the ram section 40 and the load at a 2:1 mechanical advantage compared to the pull of carriage 42 on runs 113, 113'. Hence, so long as carriage 42 can move upwardly relative to section 40, cylinder 56 will remain "bottomed" in section 34. As plunger 60 is thus moved upwardly from its completely retracted position in FIG. 5 to the partially extended position of the mast shown in FIG. 4, which may represent for example a distance of 1 1/2

inches of plunger movement, sheaves 80, 80' move upwardly with the plunger and through chains 62, 62' thereby lift section 40 at a 2:1 ratio relative to plunger movement, which for the example given would raise section 40 a distance of three inches. This upward movement of section 40 relative to section 34 separates arms 64, 64' from arms 68, 68' so that chains 58, 58' lift carriage 42 at a 2:1 ratio relative to section 40 at the same time chains 62, 62' are lifting section 40. Hence, carriage 42 is lifted at a 4:1 ratio relative to the rate of expansion of ram 44, and thus in the example given carriage 42 is lifted six inches above its ground level starting position shown in FIG. 5.

Preferably, mast 30 is designed so that arms 64, 64' in the completely retracted condition of the mast are disposed below the uppermost structure of guard 38 of truck 32 by a distance of say three inches (as best seen in FIG. 6). Hence, by the time arms 64, 64' are raised flush with the clearance limit of the truck, carriage 42 will have been lifted twice this distance, thereby providing an initial range of "full free lift" of carriage 42 (6 inches) in the aforementioned example) before the uppermost structure of mast section 40 is lifted above the clearance height of the truck and thereafter determines the effective overhead operating clearance required for truck 32.

As plunger 60 moves further upwardly in cylinder 56 between the FIG. 4 and FIG. 3 positions thereof, this further extension of ram 44 continues to lift section 40 at the 2:1 ratio relative to plunger 60 while the separation of sections 40 and 34 continues to simultaneously lengthen runs 112, 112' of chains 58, 58' between sheaves 70 and 74, thereby lifting carriage 42 further upwardly on section 40 at the 4:1 ratio relative to ram extension. When arms 64, 64' reach approximately 47 1/2 percent of their travel toward the full lift position of FIG. 2, i.e., when they reach their position as shown in FIG. 3 (which may represent about 86 inches of upward movement of forks 66 from their initial starting position), carriage 42 hits stops on section 40. When this occurs, what may be referred to in the art as the "normal two-rail action" of mast 30 terminates. In other words, at this point in the vertical extension of mast 30, the load being carried on forks 66 catches up with the upper end of mast 30. From this point on upward a "true free lift" action will be obtained, i.e., the load on the carriage will move upwardly at the same rate as the upper end of the mast.

As ram 44 continues to expand to its fully extended position shown in FIG. 2, the upward movement of sheaves 80, 80' relative to cylinder 56 causes chains 62, 62' to continue lifting section 40 at a 2:1 rate relative to cylinder 56. Since carriage 42 can no longer move up any further on section 40, the further separation of arms 64 and 68 and consequent lengthening of runs 112, 112' shortens the runs 114, 114' and 116, 116' on which cylinder 56 is suspended. Hence, after carriage 42 reaches the top of section 40, the entire ram 44 is lifted upwardly on the lower mast section 34 by chains 58, 58' due to the separation of arms 64 and 68. Thus, the load continues to be lifted on carriage 42 at a 4:1 ratio relative to ram expansion.

It is to be noted that during this final stage of vertical mast extension, section 40 is lifted clear of section 34 and becomes widely separated therefrom, as best seen

in FIG. 1. Hence, in the upper load lifting range of mast 30, the sole connection of carriage 42 to truck 32 is through ram 44 and chains 58, 58' and 62, 62', rather than additionally through a series of telescopically interengaged mast sections as is conventional in the prior art. The final stage of lifting terminates when sleeve 108 hits a stop at the upper end of cylinder 56. During all of the preceding mast extension stages, section 40 slides vertically upwardly in bracket 102 and sleeve 108 slides upwardly along keys 104 and 106.

The load lowering sequence of mast 30 is the reverse of the aforementioned lifting sequence and is effected by controlled release of hydraulic fluid from cylinder 56 via line 110.

Throughout the load lifting range of mast 30, the load suspended on the cantilever forks 66 of carriage 42 exerts a counterclockwise bending moment (as viewed in FIGS. 1-5) on apron 50 which is transmitted to section 40 by the vertically spaced carriage rollers 46, 46' and 48, 48'. This load induced bending moment is, in accordance with a principal feature of the present invention, counterbalanced by a substantially equal bending moment developed by the vertical downwardly directed reaction force transmitted in tension in runs 112, 112' and acting on arms 64, 64' at the point where chains 58, 58' are trained respectively around sheaves 70, 70'. Sheaves 70, 70' are supported on arms 64, 64' at points spaced rearwardly from an imaginary neutral plane defined by runs 113, 113' by a horizontal distance substantially equal to the horizontal spacing between this plane and the center of gravity of the average load on forks 66. Since the counterbalancing force is oriented parallel to and in the same direction as the gravitational force exerted on the load which acts vertically on forks 66 at the load center of gravity, and since these two forces are substantially equal regardless of the weight of the load and act through equal but opposite moment arms, the counterbalancing moment is always substantially equal to the load induced unbalancing moment. This counterbalancing moment is applied to the upper end of section 40 by the rigid cantilever connection of arms 64, 64' to rails 54, 54' respectively. Ram 44 is thus relieved of the cantilevered load bending moment which otherwise would exert a bending stress between plunger 60 and cylinder 56, and between section 40 and bracket 102. Hence, ram 44 "sees" only a vertical compression loading from the resultant of the forces applied to it by chains 58, 58' and 62, 62'. By eliminating the need for a continuously interconnected telescopic assembly of rail sections hitherto required to take the bending moment exerted by the cantilevered load, the supporting structure of mast 30 need constitute only ram 44 loaded in compression and chains 58, 58' 62, 62' loaded in tension, which is their natural and most efficient mode of loading. Several additional benefits in terms of structural and operational efficiency are obtained throughout the mast and associated truck structure as set forth in the following detailed description of mast 30, ram 44 and carriage 42 as well as in the subsequent description of the second, third and fourth mast embodiments.

LOWER MAST SECTION 34

Referring to the structural views of FIGS. 6-13 inclusive, which illustrate an exemplary but presently

preferred construction of mast 30, the pair of vertically extending rails 35, 35' of the fixed mast section 34 (FIG. 10) are channel members disposed with their respective grooves 98, 98' facing inwardly toward one another to form tracks for receiving the ram guide rollers 96 and 96' respectively. Rails 35, 35' are rigidly interconnected at their lower ends by a mast mounting bracket 120 (FIG. 6) consisting of a pair of horizontal cross braces 122 and 124 welded to the rear edges of rails 35, 35' and a pair of spaced vertical hanger plates 126 welded between braces 122, 124 and notched to rest on the front mast mounting pin 36 of truck 32. Rails 35, 35' are rigidly interconnected at their upper ends by a bracket 130 (FIG. 10) comprising a semi-cylindrical plate 132 connected by wing brackets 134, 136 to the fronts of rails 35, 35' respectively. The ram guiding rollers 90, 94 have their axles respectively journaled in spaced upright plates 138 and 140 mounted on bracket 130. The rear cross brace for the upper end of section 34 is part of the framework of lower arms 68, 68' and includes a cross brace 142 (FIGS. 8 and 10) connected at one end to a pair of horizontally spaced vertical plates 146', 148' of arm 68' (FIG. 8) and at the other end to similar plates 146, 148 of arm 68. Sheaves 76, 76 are respectively journaled between plate 146', 148' and 146, 148. The rear ram guide roller 92 is journaled between a pair of upright plates 162, 162' fixed on plate 142. Arm 68' has rearwardly converging stringers 150', 152' (FIG. 8) secured at their forward ends to plates 142', 146' and 148' and at their outer or rear ends to a pair of spaced plates 154', 155' between which sheave 74' is journaled. Plates 142', 146', and 148' and stringer 152' are welded at their inner ends to rail 35' of mast section 34. Arm 68 is constructed in like manner.

Each arm 68, 68' also forms a part of the overhead guide framework 38. Thus, the overhead tubular stringers 156', and 156, 158', 158 of guard 38 are connected at their forward ends respectively to vertical spacers 160' and 160 which are bolted to stringers 152' and 152. Stringers 158' and 158 also extends forwardly to a bolted connection with a plate 144 which in turn is bolted to plate 142. The downwardly inclined rear stringers 162, 162' (FIG. 1) of framework 38 are secured directly to the counterweight structure at the rear end of truck 32. Guard 38 through its above separable bolted connection to mast section 34 maintains the mast in fixed upright position perpendicular to the wheel base of truck 32. Due to the pivotal suspension of section 34 on pin 36, mast 30 exerts only a vertical loading on the forward end of truck 32 and this is applied closely adjacent the front wheels of truck 32. Any tilting loads imposed by the mast are transmitted from the mast solely through guard 38 to the rear of the truck, and hence the truck frame is isolated from such loading.

UPPER MAST SECTION 40

Rails 54, 54' (FIGS. 6, 8, 9, 11 and 13) of moveable mast section 40, like rails 35, 35', are of channel section but are arranged with their grooves 52, 52' facing outwardly (FIG. 9) to receive the two pairs of vertically spaced carriage rollers 46, 48 and 46', 48' respectively. Rails 54, 54' are spaced horizontally apart so as to receive rails 35, 35' therebetween so that section 34

can nest within section 40 in the collapsed, telescoped condition of the mast described previously. Rails 54, 54' are rigidly interconnected at their lower ends by a front cross brace 100, and at their upper ends by the cross bracing interconnecting arms 64, 64'. Each of the arms 64 and 64' is of like construction, arm 64' comprising an upper stringer 170' (FIG. 8) turned down at its outer end and having a pair of spaced vertical plates 172' welded thereto between which sheave 70' is journaled. Arm 64' also has a lower stringer 174' joined at its outer end to plates 172' and at its inner end to another pair of spaced vertical plates 176' and 178' between which sheave 72' is journaled. Stringer 170' as well as plates 176' and 178' are welded to the associated rail 54' to provide a rigid cantilever connection of arm 64' to section 40. The arms 64 and 64' are cross braced in their rearwardly diverging relation (FIG. 9) by a horizontal plate 180 which extends between and is welded to stringers 170 and 170' and by a V-shaped strut 182 welded at its ends to plates 178 and 178' and along its upper edge to the undersurface of the plate 180. A pair of inclined plates 184 and 184' are welded to the upper ends of rails 54 and 54' respectively over grooves 52 and 52' respectively so as to serve as stops for rollers 46, 46' and thereby define the upper limit of travel of carriage 42 on section 40.

RAM STRUCTURE

Referring to FIGS. 14-18 inclusive, ram 44 preferably comprises only two main parts, i.e., cylinder 56 and plunger 60, each of which comprises a hollow tubular member to obtain a maximum strength to weight ratio. Cylinder 56 is closed at its lower end by a plate 200 and is open at its upper end to telescopically receive plunger 60. Plunger 60 is closed at its upper and lower ends by cap plates 202 and 204 respectively and has its lower end inserted within and fixed to guide sleeve 108. Sleeve 108 does not directly engage the inner wall of the bore 205 of cylinder 56 but rather has a relatively large radial clearance with bore 205. The anti-rotation sliding interengagement of sleeve 108 and cylinder 56 is obtained by providing a pair of accurately machined diametrically opposed external key ways 206 and 208 in sleeve 108 which slideably receive guide keys 104 and 106 which in turn are received in internal key ways 210 and 212 machined in bore 205 of cylinder 56. Keys 104 and 106 are axially retained by a collar 214, the outer lower edge of which seats on a shoulder 216 at the junction of bore 205 with a counterbore 218 of cylinder 56. The upper ends of keys 104 and 106 have a dovetail 220 which slips into a radial slot in the outer periphery of collar 214, the inner wall of which is inclined complementary to dovetail 220 so that keys 104 and 106 are captured between cylinder 56 and collar 214. A conventional packing gland assembly 222 is secured between collar 214 and a nut 224 which threads into the upper end of cylinder 56.

The above described ram construction is economical to manufacture since only key ways 206, 208, 210 and 212 and keys 104 and 106 need be accurately machined due to the relatively wide clearance between sleeve 108 and cylinder 56. Keys 104 and 106 thus not only prevent relative rotation between cylinder 56 and plunger 60 but also serve as the principal slide bearing between these two ram parts. Packing ring 226 of gland

222 and resilient seal ring 228 carried by nut 224 also help to guide plunger 60 in its vertical travel within cylinder 56 but they can accommodate fairly rough tolerances in plunger 60 since they are made of flexible packing material to serve as a sliding seal to prevent leakage of the hydraulic fluid admitted to the working chamber of the ram via line 110.

GUIDE BRACKET 102

As best seen in FIGS. 6, 8, 9, 11, and 13, bracket 102 includes a horizontal crosshead 240 (FIGS. 9 and 14) secured by bolts 242 to cap 202 of plunger 60, and a rectangular front frame consisting of two vertical plates 244 and 244' and top and bottom horizontal braces 246 and 248 (FIGS. 9 and 11). Brace 246 is welded to the front face of crosshead 240 so that plates 244 and 244' extend parallel to and spaced outwardly from the front faces of rails 54 and 54' respectively (FIG. 9). Bracket 102 also includes vertically extending side plates 250 and 250' (FIG. 9) secured along their forward edges to plates 244 and 244' respectively and disposed in closely spaced relation between rails 54 and 35 and 54' and 35' respectively. Bracket 102 has a series of four wear pads for sliding engagement with each rail 54, 54', these pads being arranged in vertically spaced pairs 252', 254', and 256', 258' to slideably bear against the front and rear surfaces of rail 54' (FIGS. 9 and 13). Pads 252' and 254' are fixed to plate 244' and pads 256' and 258' to a flange 251' (FIG. 9) of plate 250', pads 252-258 being fixed in like manner to parts 254 and 250. Bracket 102 is thus capable of guiding vertical travel of mast section 40 relative to ram 44 and thus provides a safety factor for off-center loads and chain malfunctions in that it can withstand any unbalanced bending stresses imposed by carriage 42 on section 40 within the capabilities of ram 44 to accept such bending stresses.

CHAIN REEVING STRUCTURE

Sheaves 78 and 78' are supported by a suitable bracket 260 (FIG. 10) fixed to the outer surface of cylinder 56 near the lower end thereof. Bracket 260 carries the spindles (not shown) for sheaves 78 and 78' arranged so that the sheaves are mounted at an angle corresponding to the associated arms 68, 68'. Bracket 260 also has suitable spindles (not shown) below sheaves 78 and 78' for mounting the ram guide rollers 96 and 96' adjacent the lower end of cylinder 56 with these rollers disposed to track in grooves 98, 98' of rails 35 and 35' respectively.

Due to the slight difference in the angular orientation of sheaves 70 and 70' on arms 64 and 64' relative to sheaves 74 and 74' on arms 68 and 68', runs 112 and 112' are provided with suitable swivel or rigid connectors 270, 270' (FIG. 8) between the upper and lower arms to angularly align the upper and lower portions of these runs with the associated sheaves and thereby eliminate twisting of these runs.

The connection 88 and 88' of chains 58 and 58' with the carriage 42 is best seen in FIGS. 6 and 20 and consists of bolts 89 and 89' adjustably secured to arms 264 and 264' respectively which extend rearwardly from the main links 266 and 266' of the carriage tilting mechanism described hereinafter. The connections 86, 86' of the other ends of chains 58, 58' to mast section

34 consists of bolts 266, 266' respectively secured between chain runs 116 and 116' (FIG. 6) and plates 134 and 136 of bracket 130 (FIG. 10). The connections 84 and 84' of chains 62 and 62' to cylinder 56 are best seen in FIGS. 8 and 13 and consist of suitable brackets 272, 272' welded to the outer surface of cylinder 56 near the upper end thereof to which are secured chain connecting bolts 274 and 274' respectively. The connections 82 and 82' at the other ends of chains 62 and 62' with the upper mast section 40 (FIG. 11 and 12) consist of suitable brackets 276, 276' welded to plate 100 at its junctions with rails 54 and 54' and chain connector bolts 278, 278' respectively secured to these brackets. Sheaves 80 and 80' are journaled on axles between spaced plates 280, 282 and 280', 282' (FIGS. 9 and 11) mounted on the opposite sides of crosshead 240 and angularly oriented so that sheaves 62 and 62' are properly aligned with the associated fore and aft runs of chains 62 and 62'.

ТИЛТИНГ САРРИДЖ 42

Сарридж 42 of mast 30 may be a conventional non-tilting carriage but preferably comprises a novel tilting carriage constructed in accordance with the present invention as shown by way of example in FIGS. 6 and 19-22 inclusive. Referring to FIGS. 6 and 20, carriage 42 has a pair of main links or tie bars 266 and 266' suspended respectively from chains 58 and 58' as described previously. Tie bar 266 extends vertically adjacent the outer side of rail 54, and bar 266' is suspended in like manner adjacent the outer side of rail 54'. Carriage rollers 46 and 48 are respectively journaled on axle pins 290 and 292 which extend through and are secured to the upper and lower ends respectively of tie bar 266. Upper and lower pivot links 294 and 296 are pivoted at their rear ends on pins 290 and 292, axially intermediate the tie bar and roller, and extend forwardly of the mast in converging relation to one another. The forward ends of links 294 and 296 extend between, and are pivotally connected by vertically spaced pins 298 and 300 respectively to, a pair of vertical plates 302 and 304 which form part of apron 50 of carriage 42 (see also FIG. 19). Plates 302 and 304 are separated by spacers 306 and 308 (FIGS. 19 and 20) and are welded in notches of upper and lower apron rails 310 and 312, the front faces of apron rails 310 and 312 being flush with the front faces of plates 302 and 304. The left-hand side of carriage 42 has like parts 290'-308' inclusive (FIG. 6).

The upper edge of rail 310 is provided with a series of notches 314 adapted to removably receive the upper hook ends 316 (FIG. 20) of the L-shaped forks 66. The upright backs 318 of forks 66 bear against rails 310, 312 to provide the cantilever support for the forwardly projecting tines 320 of forks 66. Various other load lifting attachments may be removably secured to carriage 42 in like cantilever fashion.

Carriage 42 is equipped with two hydraulic rams 322 and 322' respectively mounted on tie bars 266 and 266' inwardly of the associated tie bar so as to swing in the space available between the respective tie bars and grooves 52, 52' of the associated rails 54, 54' (FIGS. 20 and 22). Ram 322 includes a cylinder 324 pivoted at its upper end on a pin 326 secured to bar 266 just beneath link 294 and a plunger 328 hydraulically reciprocated

in cylinder 324 and extending from the lower end thereof. The lower end of plunger 328 is pivotally connected by a pin 330 to a block 332 fixed to an apron crank arm 334 which in turn is secured at its forward end to plate 304 and spacer 308. Ram 322' is mounted in like manner between bar 266' and apron 50.

Rams 322, 322' are conventional and of the double acting type supplied with pressure fluid from a common source via hose lines 336, 336' and 338, 338' which are connected to supply-exhaust lines 340 and 342 (FIG. 19). Lines 340 and 342 are clamped by a bracket 346 (FIG. 6) to the outer side of bar 266' and then run upwardly over a sheave 348 (FIGS. 6 and 7) journaled on a pin 350 of a housing 352 which in turn is spring mounted on plate 176' by a bracket 354, pin 356 and spring 358 arranged as shown in FIG. 7. Lines 340, 342 then run downwardly to a dual sheave 360 carried on a bracket 362 suitably secured to cylinder 56 near the lower end thereof. Lines 340, 342 then run upwardly to a connector 364 (FIG. 6), and then run back downwardly to truck 32 to a connection with the source of hydraulic pressure fluid, a suitable hydraulic control mechanism being provided convenient to the truck operator to control tilt of carriage 42 independently of load lifting on mast 30.

Rams 322 and 322' are controlled to operate identically and simultaneously to extend and retract their plungers 328, 328' to thereby articulate the associated carriage framework which in turn acts in the manner of a four-bar linkage whereby fork tines 320, 320' are moved through a range of tilting movement as illustrated in FIG. 22 by the solid and broken line views thereof. Only the operation of the right-hand linkage will be explained since the same explanation applies to the left-hand linkage. Tie bar 266 acts as the fixed link of the four-bar linkage since it is anchored by carriage rollers 46 and 48 tracking in rail groove 52. In order to lower forks 66 toward their extreme downwardly tilted position shown in broken lines in FIG. 22, ram 322 is operated to draw plunger 328 upwardly into cylinder 324, thereby exerting through crank 334 a clockwise moment on apron 50 which pivots links 296 and 298 upwardly or counterclockwise as viewed in FIGS. 20 and 22. To tilt forks 66 in the opposite direction toward their extreme upwardly inclined position shown in solid lines in FIG. 22, ram 322 is operated in the opposite direction to force plunger 328 downwardly so that a counterclockwise moment is exerted through crank 334 on apron 50.

The above described tilting carriage mechanism provides an economical and efficient means for varying the attitude of fork tines 320, 320' or other load lifting attachment carried on apron 50 without requiring that mast 30 be tilted from its fixed orientation relative to truck 32, thereby retaining the operating capabilities of a truck equipped with a conventional tilting mast while eliminating several disadvantages of such masts. Due to the generally vertical orientation and limited swing required of rams 322, 322', they may be compactly nested inwardly of tie bars 266, 266' in rail grooves 52, 52' of rail 54, 54', thereby reducing the overall width of the mast. Since the mast normally nests between the front tires of the lift truck, this reduction in mast width permits a concomitant reduction in the overall width of the truck to better facilitate operation in narrow aisles and cramped storage spaces.

It is also to be noted that apron 50 forms the shorter of the two "long" links of the four-bar linkage. This orients the center of pivotal motion of the load outside the linkage at the intersection P of the imaginary lines 370 and 372 (FIG. 22) projected perpendicularly from two positions of the same point on the apron in its range of tilting movement. Hence, the load pivot point is extended out to point P which is preferably near or coincident with the center of gravity of the average load to be carried on forks 66. Therefore, the tilting motion imparted to the forks 66 neither raises nor lowers the load but rather pivots the same about its center of gravity. Due to this feature, small size rams 322, 322' are sufficient to articulate the carriage since they need only overcome the frictional resistance of the carriage parts. The four-bar linkage also permits a relatively short stroke ram 322 to be used for obtaining a relatively large angular range of motion of the carriage. These features in turn lead to other economies of structure as well as to reduced drain on the truck pump and power source.

With the aforementioned linkage suspension, the upper and lower ends of apron 50 move in opposite directions to tilt the forks, which minimizes the space required between the mast and apron for a given range of tilting motion and thus reduces the load moment arm. The four-bar tilting linkage of carriage 42 also permits carriage rollers 46, 48 to be spaced vertically farther than the height of apron 50 to better distribute the bending load exerted by forks 66 along the rails of mast section 40. Although other articulations of rams 322, 322' may be used, such as directly between bar 266 and apron 250, the provision of crank arm 334 to couple ram 322 to apron 50 enables the ram to retain its preferred vertical orientation while acting between the two long links of the four-bar linkage, thereby obtaining a force multiplication for rams 322, 322'.

Carriage 42 also cooperates with mast 30 to improve the performance of lift truck 32 in several respects. By using a tilting carriage, mast 32 need not be mounted for tilting movement on truck 32 and hence the position of the load on carriage 42 need not be shifted away from the center of the truck. This improves the stability of the mast and truck and increases the capacity of the mast over one which must tilt. Also, since mast 30 need not swing in order to tilt the load, the inertia forces tending to produce whip action of the mast are greatly reduced. The combination of the tilting carriage 42 and non-tilting mast 30 also permits lower chain orienting arms 68 to be fixedly attached or anchored near their outer ends to the lift truck, which in turn enables them to be incorporated with the overhead guard framework 38, thereby relieving mast section 34 of the bending stress imparted to arms 68, 68' and providing greatly increased side support for the mast so that the mast and truck can operate at a much greater angle of side tilt.

SUMMARY

From the foregoing description, it will now be apparent that mast 30 and tilting carriage 42, both individually and in combination with truck 32, provide many features and advantages over previously available lift truck hoisting mechanisms. The deflection of conventional masts due to the cantilever support of the load on the usual lifting forks is eliminated without sacrificing the desirable load handling capabilities of

lift forks. The hydraulic ram 44 is placed solely under a compressive load under normal loading conditions by the action of the tension forces in the load lifting chains 58, 58', enabling the ram to be used as a beam in the mast without any increase in the size of the ram parts over what is required to handle the hydraulically imposed stresses. Since the counterbalancing chains are also the load lifting chains, the balance of mast 30 is unaffected by changes in the load. Even when truck 32 is operated on inclined surfaces, the resulting inclination of mast 30 results in only a very minor shifting of the center of gravity of the load relative to the forks, and this is insufficient to significantly affect the counterbalancing force system of mast 30. For example, with a 10 degree tilt of mast 30, either forward or aft from vertical and with a 6,000 pound load supported on forks 66, the vertical component of 5,900 pounds from this load is still counterbalanced through chains 58, 58' and arms 64, 64' and the component of force acting perpendicularly to mast 30 resulting from this load represents only 1,000 pounds. Hence, the column strength of mast 30 need only exceed that necessary to withstand the 1,000 pound force component even when the mast is tilted 10° fore or aft of vertical. This requirement is readily accommodated through the inherent bending strength of ram 44 and guide 102. In fact, in a mast 30 constructed as shown generally to scale in FIG. 1, a 4:1 safety factor or 4,000 pound column strength has been provided for a 10° tilt angle while using a much less expensive mast construction than hitherto available for a similar load lifting capacity.

The outwardly diverging counterbalance arms 64, 64' and associated chain reeving arms 68, 68' orient the load lifting chains 58, 58' to serve as guy wires for the extended mast so the same can successfully operate at a relatively large angle of side tilt and with exceptionally large side load offsets. For example, when the diverging arms 64, 64' and 68, 68' spread the counterbalance chains 58, 58' out by the entire width of truck 32, the usual permissible side load offset is approximately doubled. As long as the center gravity of the load on forks 66 is between the restraining lines 58, 58', the bending moment caused by the side load offset will also be balanced through the action of whichever of the chains 58, 58' and associated counterbalancing arms 64, 64' is disposed opposite from the direction of the side load offset. Even if the load center of gravity should be laterally outside the chains 58, 58', the 4:1 column strength safety factor is available to permit mast 32 to safely withstand such extreme conditions. Even when the angled lower arms 68, 68' are not anchored to truck 32, they provide better control of the counterbalancing system both fore and aft and from side to side.

In addition to the aforementioned manufacturing economies, keys 104, 106 enable the lift ram 44 to withstand torsional stresses and thereby prevent rotation of the carriage 42 relative to truck 32 in the separated condition of mast sections 34, 40, thus insuring precise control of carriage 42 and preventing disorientation of the counterbalancing forces, factors which are vital to the elimination of the conventional intermediate continuously engaged mast sections. The reduction in mast and ram parts effects a weight saving

of 35 percent which in turn permits much higher lifts with increased load capacity. For example, the drive axle load on truck 32 can be reduced as much as 1,200 pounds for a mast having a load lifting range of 20 feet and a load lifting capacity of 6,000 pounds.

The chain counterbalancing of mast 30 also drastically reduces the frictional resistance to extension of the mast due to reduced bending forces being carried through the bearing points of the mast. The reduced friction and reduced structural deadweight increases the efficiency of the load lifting mechanism from about 41 percent to about 67 percent. Hence, less power is required to raise the pay load, faster lift speed is obtained with smaller ram parts and a smaller fluid reservoir is required in the truck. The simplicity of the structure of mast 30 and the fewer number of parts required in the mast permit greater standardization of mast components and more compact mast designs resulting in greater design flexibility and a larger range of capabilities for a given unit.

By using a tilting carriage 42, mast 30 can be mounted rigidly to truck 32 and the existing overhead guard can be tied directly into the lower arms 68, 68', providing both greater protection for the operator and better structural support for the mast. Also, the position of the load can be maintained near the center of support of the truck 32, which improves truck stability. Since a minimum of load carrying structure is set in motion when tilting the load, inertia forces on the supporting unit caused by tilting movement of the load can be virtually eliminated. Also, the mast bending stresses are carried overhead by frame 38 directly back to the counterweight region of truck 32 instead of through the mast anchor and truck frame. Therefore, less deadweight material is required in the truck frame. The combination of the tilting carriage 42 and rigidly mounted mast 30 thus provides increased mast and truck capacity at lower cost without sacrificing operating versatility, safety or reliability.

MODIFICATIONS

The foregoing principles and features of the load lifting mechanism of the present invention embodied in mast 30, tilting carriage 42 and truck 32 can also be applied to load lifting masts having a "three-rail" load lifting capacity, as illustrated by the third embodiment 500 of an extensible mast in accordance with the present invention shown semi-schematically in FIGS. 24 and 27, or to an extensible mast having only a "two-rail" load lifting capacity as shown semi-schematically in the fourth embodiment 600 of the invention illustrated in FIGS. 25 and 28. Also, the arrangement of the carriage, mast sections and hoisting chains employed in mast 30 can be applied to a conventional non-counterbalanced mast as illustrated in the second embodiment 400 of the invention as shown semi-schematically in FIGS. 23 and 26.

MAST 400

Referring to FIGS. 23 and 26, mast 400 comprises four telescopically, slideable and continuously interengaged dual-rail mast sections 402, 404, 406, 408 which are adapted to take the bending load imposed by the load carried on the cantilever forks of the carriage 42. A two-part ram 440 similar in most respects to ram

44 is used to vertically extend mast 400 and is suspended by a pair of chains 410, 410' corresponding to chains 58, 58' respectively. Thus, one end of each chain 410, 410' is connected at 412, 412' to the upper end of lowermost section 402. Chains 410, 410' extend downwardly from 412, 412' to and under sheaves 78, 78' carried on cylinder 56 of ram 440, then run upwardly to sheaves 414, 414' journaled on uppermost mast section 408 near the upper end thereof and then run downwardly to connections 416, 416' with carriage 42. The vertically spaced rollers 46, 46' and 48, 48' of the carriage track in the outwardly facing channels of the rails of mast section 408, similar to the arrangement in mast 30. A second set of chains 420, 420' are connected at 422, 422' to cylinder 56 of ram 440 and extend upwardly therefrom over sheaves 424, 424' which, like sheaves 80, 80', are journaled on shafts carried by a crosshead 426 fixed to the upper end of plunger 60 of ram 440. Chains 420, 420' are connected at their other ends at 428, 428' to the lower cross brace 100 of upper mast section 408.

The intermediate mast sections 404 and 406 may be directly connected to ram 44 by a cross brace 430 (FIG. 26) connected between the rails of section 404 and the upper end of cylinder 56, and by extending shaft 432 on which sheaves 424, 424' are journaled OUT to a connection with the inner sides of the rails of section 406. Suitable slots 434 may be provided in the rails of section 404 to receive shaft 432 in the collapsed condition of the mast.

Mast 400 is extended in a manner similar to mast 30 in that during initial upward movement of plunger 60 in cylinder 56, section 408 is lifted by chains 420, 420' due to the upward movement of sheaves 424, 424' relative to cylinder 56. This simultaneously raises sheaves 414, 414' relative to sheaves 78, 78', thereby raising carriage 42 along the rails of section 408 until the carriage hits suitable stops defining the upper limit of its travel on section 408. From this point on upward, further extension of plunger 60 relative to cylinder 56 continues to raise upper section 408 relative to sheaves 78, 78', causing the runs of chains 410, 410' between sheaves 414, 414' and 78, 78' to lengthen, thereby shortening the runs of chains 410, 410' between sheaves 78, 78' and connections 412, 412' so that cylinder 56 is lifted relative to the lowermost mast section 402. Section 406 is raised directly with upward movement of shaft 432, and section 404 is likewise raised directly with cylinder 56 by brace 430. Upon controlled release of hydraulic fluid from ram 44, carriage 42 is lowered in reverse of the mast extension sequence.

The chain rigging arrangement of mast 400 thus corresponds to that of mast 30 and provides a 4:1 cylinder ratio which makes the size of ram 44 required for the force and beam strength compatible with a simple two-part cylinder. As in the case of mast 30, mast 400 functions as a true free lift mast after carriage 42 hits the stops at the top of mast section 408, which occurs at a relatively low position, until the upper limit of the load lifting range of the mast.

MAST 500

Referring to FIGS. 24 and 27, mast 500 comprises a simple two-part ram 502 made up of an outer cylinder

504 mounted on the front pin 36 of truck 32, and a plunger 506 telescopically received in cylinder 504 in the manner of the previously described plunger 60. A pair of rearwardly outwardly diverging chain orienting arms 508, 508' are cantilevered at their forward ends to cylinder 504 near its upper end and are respectively connected at their outer ends by laterally spaced links 510, 510' (FIG. 27) to the frame of truck 32. A second pair of combined chain orienting and counterbalancing arms 512, 512' are cantilevered at their forward ends to the upper end of plunger 506 to a crosshead guide 524 similar to guide 102 and extend rearwardly and diverge outwardly relative to one another therefrom for a distance greater than arms 508, 508'.

With the above arrangement, an upper mast section identical to section 40 described previously may be used as the single mast section of mast 500. Alternatively, a single mast section 514 may be constructed as shown in FIGS. 24 and 27 wherein the vertical rails 516, 516' of section 514 comprise I-beam members connected near their lower ends by a front brace 518 and at their upper ends by a top brace 520. A pair of upper counterbalance arms 522, 522' are fixed at their inner ends to the upper ends of rails 516, 516' and extend rearwardly therefrom in outwardly diverging relation above and generally coterminous with the adjacent arms 512, 512'. Crosshead guide 524 is fixed to the top of plunger 506 and has dependent arms 526, 526', each supporting a pair of vertically spaced rollers 528, 530 and 528', 530' which track in the inwardly facing channels of rails 516, 516' respectively. Mast section 514 is suspended by a pair of chains 530, 530' which are connected at one end to brace 518 and then run upwardly over sheaves 532, 532' journaled on and between plunger 506 and bracket 524, thence outwardly to sheaves 534 and 534' journaled about midway out on arms 512, 512', respectively, thence downwardly to a fixed connection with the outer end of arms 508, 508', respectively. A load lifting carriage 40, preferably identical to carriage 42, has vertically spaced rollers 542, 544 and 542', 544' which track in the outwardly facing channels of rails 516, 516', respectively. Carriage 540 is suspended on a pair of chains 544, 544' which are connected at one end to carriage 540 and then run upwardly over sheaves 546, 546' respectively journaled at the inner ends of arms 522, 522', thence outwardly to sheaves 548, 548' journaled at the outer ends of arms 522, 522' respectively and thence downwardly to fixed connection with the outer ends of arms 512, 512' respectively.

In operation, mast 500 is extended by controlled application of hydraulic pressure fluid to ram 502 to extend plunger 506 in the same manner as ram 44. Upward movement of sheaves 532, 532' and 534, 534' with plunger 506 lifts mast section 514 at a 2:1 ratio relative to the rate of ram expansion. The upward movement of section 514 relative to plunger 506 lifts sheaves 545, 546' and 548, 548' relative to arms 512, 512', causing chains 544, 544' to lift carriage 540 upwardly relative to section 514 at a 2:1 ratio relative to section 514 and at a 3:1 ratio relative to plunger 506. Mast 500 is designed such that when section 514 reaches the upper limit of its travel on guide 524, carriage 540 also reaches the upper limit of its travel on section 514. The lowering sequence is the reverse of the raising sequence.

Mast 500 thus employs a counterbalanced telescoping ram in which the main supporting structure is ram 502 in compression and the lifting chains 530, 530' and 544, 544' in tension, which is their normal function. 5 Like mast 30, the load lifting chains 530, 530' and 544, 544' exert downward forces on their respectively associated counterbalancing arms 512, 512' and 522, 522' which in turn convert these forces to two moments which balance the bending moment imposed by 10 the cantilevered load on carriage 540 and transmitted through its rollers to section 514. However, the additional pair of counterbalancing arms 512, 512' apply a counterbalancing moment to guide 524 so that bending loads can be applied to guide 524 and balanced directly 15 at this point so that the plunger 506 only "sees" a pure vertical compression loading. Since chains 530, 530' carry more weight than chains 544, 544', sheaves 534, 534' are spaced inwardly from sheaves 548, 548' to reduce the effective moment arm of the downward 20 forces applied by chains 530, 530'. Since an upwardly acting moment results from chains 544, 544' acting upwardly on the outer ends of arms 512, 512', there is a further reduction in the net counterbalancing moment 25 exerted by arms 512, 512' on guide 524. The counterbalancing system thus reduces the beam strength required in ram 502, making possible the use of the ram parts as part of the mast supporting structure as well as the hydraulic power unit for extending the mast.

30

MAST 600

Referring to FIGS. 25 and 28, mast 600 employs a simple two-part ram 602 having an outer cylinder 604 mounted at its lower end on pin 36 of lift truck 32. A plunger 606 is telescopically received in cylinder 604 in the manner of plunger 60 in cylinder 54.

Mast 600 uses the same single vertically moveable mast section 514 as mast 500, but in mast 600 section 514 is mounted directly on ram 602 by fixing brace 520 to the upper end of ram 606. Carriage 540 tracks vertically on mast section 514 and is extended by chains 544, 544' as described in connection with mast 500, but the lower ends of these chains are either directly connected to truck 32 as shown or to arms (not shown) similar to arms 508, 508' cantilevered to cylinder 604. A crosshead 610 is fixed to the upper end of cylinder 602 and carries rollers 612, 612' which track respectively in the inwardly facing channels of the rails 516, 516' of mast section 608. A lower cross brace 518 of mast section 608 is adapted to slide along the front surface of cylinder 604. Alternatively, another pair of rollers (not shown) can be mounted on cylinder 604 below rollers 612, 612' to guide section 514, which permit a smaller cylinder to be used in ram 602. If desired, a conventional mast tilting ram 614 may be connected between cylinder 604 and truck 32 to vary the angular orientation of mast 600 relative to truck 32. Since crosshead 610 is mounted on cylinder 604 and the cylinder in turn is non-rotatably mounted on truck 32, ram 602 need not have keys 104, 106.

In operation, mast 600 is extended by controlled application of pressure fluid to ram 602 in the same manner as ram 44. However, section 514 is directly lifted by plunger 606 at the same rate as the plunger. This causes chains 544, 544' to lift carriage 540 upwardly along section 514 at a 2:1 ratio relative to the rate of ram expansion. The bending moment imposed

65

by the load on carriage 540 and transmitted through the carriage to section 514 is again counterbalanced by the rear vertical runs of chains 544, 544' acting on the rear sheaves 548, 548' of arms 522, 522' so that ram 602 is subjected solely to the compression loading exerted through plate 520 on plunger 606.

If desired, mast 600 may be tilted by actuating tilt ram 614. When chains 544, 544' are directly connected to truck 32, mast 600 should be tilted before carriage 540 is near the upper limit of its travel on section 514. However, if these chains are free of truck 32 and connected back to cylinder 604 in the manner of chains 58 of mast 30 or as mentioned above, with reference to arms 508, 508' then mast 602 can be tilted with carriage 540 in any position on section 514.

From the foregoing description, it will now be evident that the invention in its broader aspects is not limited to the specific mechanisms shown and described, and that departures may be made therefrom within the scope of the accompanying claims without departing from the principles of the invention and without sacrificing its chief advantages.

It will be further understood that the horizontal distance between the neutral plane of a mast of the invention and the chain supporting rollers 70 or 548 is preferably somewhat less than the distance between the neutral plane and the center of gravity of the live load carried on the carriage in order to accommodate the gravitational force exerted on the chains 58, 58' by the deadweight of the mast structure. Since the center of gravity of this dead load is much closer to the neutral plane than that of the average live load carried on forks 66, it is necessary to take this factor into account in determining the length of the counterbalancing moment arm. For example, in the example of mast 30 described previously there is say 1500 pounds of structural weight which is always acting on chains 58, 58' even under no-load conditions. Thus, the counterbalancing moment arm may be on the order of 18 inches for a live load moment arm of about 24 inches, whereas the counterbalancing moment arm may be about 22 inches for a live load moment arm of about 30 inches. In the case of mast 30 when the same is designed to lift live loads ranging up to 6000 pounds, utilizing such ratios will result in an equalization of the load moment and counterbalancing moment for a 3000 pound live load, the counterbalancing moment being increasingly greater than the load moment as the live load is decreased from 3000 pounds and being decreasingly less than the load moment as the live load is increased up to 6000 pounds.

Counterbalancing arms 64, 64' are preferably fixed to upper end of mast section 40 in order to permit vertical nesting of section 40 on section 34 without passage of arms 64, 64' past arms 68, 68'. However, it will be understood that arms 64, 64' may be mounted elsewhere on section 40, such as near the lower end thereof, without altering their counterbalancing effect. Also, the load lifting means cantilevered on section 40 may be fixed thereto rather than vertically movable thereon in the manner of carriage 42, although the latter arrangement is preferred in most instances since it provides a greater range of vertical lift.

I claim:

1. A load lifting mechanism for a vehicle comprising an extensible upright mast adapted to be supported at its lower end on the vehicle and including a vertically movable mast section and a hydraulic ram forming a vertical structural support member of said mast extending between the lower end of said mast and said mast section, said mast section being disposed at the upper end of said mast, means operably connecting said ram to said mast section such that said mast section is operably supported by and vertically elevated by actuation of said ram, guide means maintaining said mast section in angular alignment with the lower end of said mast via said ram, a load supporting carriage having cantilever load lifting members extending therefrom for supporting a load with its center of gravity spaced horizontally outwardly from said ram, means supporting said carriage in cantilever relationship on said mast section and vertically movable along said mast section, counterbalancing arm means fixedly mounted on and extending from said mast section in a direction generally opposite to said load lifting members, and flexible tension means operably connected at one end with said ram and at the other end with said carriage for exerting in tension a load lifting force on said carriage to cause vertical load lifting movement of said carriage in response to actuation of said ram, first and second support means mounted on said mast section and said arm means respectively and training said flexible means on said counterbalancing arm means such that said flexible means has a first run extending downwardly from said first support means to a load lifting connection with said carriage and a second run extending downwardly from said second support means at a point on said arm means spaced horizontally a predetermined distance in said opposite direction correlated with the load lifting tension force in said flexible means and connector means for operably connecting said second run to a support point remote from said mast section and fixedly associated with said lower end of said mast or with the vehicle at an elevation below said second support means such that said second run of said flexible means acting on said arm means develops a moment acting on said mast section proportional to and oppositely to the load induced moment exerted via said load lifting members, said carriage and said carriage support means on said mast section so as to substantially counterbalance load induced bending forces acting via said carriage support means on said mast section whereby said bending forces are reacted in said mast section to thereby isolate said ram from said bending forces.
2. The combination set forth in claim 1 wherein said ram comprises at least a cylinder member and a plunger member telescopically received in said cylinder member, and wherein said guide means comprises key and keyway means disposed radially intermediate said ram members and extending axially thereof in sliding engagement with at least one of said ram members to prevent relative rotation therebetween.
3. The combination set forth in claim 2 wherein said guide means also includes a crosshead secured to the upper end of the uppermost of said ram members, said crosshead having means engaging said mast section to prevent relative rotation between said ram members and said mast section.

4. The combination set forth in claim 1 wherein said counterbalance arm means comprises at least two rigid arms each rigidly fixed at one end to said mast section and extending therefrom to a free end spaced said predetermined distance in said opposite direction, said arms being spaced from one another in a direction transverse to said directions in which said load lifting members and said arms extend, said flexible tension means comprising two flexible elements associated one with each of said arms and each having said first and second runs, said second runs and said connector means being oriented relative to said mast to provide counterbalancing forces thereon in response to tilting of said mast transversely of said directions in which said load lifting members and said arms extend.

5. The combination set forth in claim 4 wherein said arms diverge from one another in said opposite direction.

6. The combination set forth in claim 5 wherein said arms are secured to said mast section in the vicinity of the upper end thereof.

7. A load lifting mast adapted to be mounted upright on a lift truck comprising an extensible framework including a plurality of mast sections, the lowermost one of said sections being adapted to be mounted on the truck to prevent relative vertical movement therebetween, a second one of said sections being movable up and down relative to the fixed section and constituting the uppermost section of said mast, said second section comprising first and second horizontally spaced upright rails, a carriage movable up and down on said second section, said extensible framework including power means operably connected to said second section for raising and lowering said second section with said carriage thereon, flexible tension means operably connected to said carriage and said second section for lifting said carriage on said second section in response to upward movement of said second section, load supporting means mounted on said carriage for movement therewith and projecting from said framework in one direction, first and second counterbalancing arms fixedly connected to the upper end of said first and second rails respectively and projecting therefrom in a direction opposite to said one direction and being spaced from one another laterally of said mast for applying fore and aft and side tilt balancing moments to said second section, and first and second support means mounted respectively on said first and second arms at a predetermined distance outwardly from said mast in said opposite direction, said support means operably connecting said flexible means to said counterbalancing member, said flexible means having first and second runs extending respectively downwardly from said first and second support means and connector means for operably connecting said first and second runs to associated support points remote from said second mast section and fixedly associated with said framework or the lift truck at an elevation below said first and second support means for applying downward forces via said first and second runs to said arms proportional to the load being supported by said load supporting means so as to counterbalance the load induced bending forces acting via said carriage rails whereby said load induced bending forces and said counterbalancing forces are reacted solely in said second section to thereby relieve the remainder of said mast components from such bending forces.

8. A load lifting carriage and mast section assembly for use on an extensible upright mast of the type adapted to be supported at its lower end on a vehicle and adapted at its upper end to support said assembly thereon and having an extending mechanism for vertically extending said mast, said assembly comprising a mast section adapted to be mounted on the upper end of said mast so as to be operably supported by and vertically elevated by actuation of said extending mechanism, guide means for maintaining said mast section in angular alignment with the upper end of the mast, a carriage including cantilever support means carried on and vertically movable along said one mast section, said carriage having cantilever load lifting members extending therefrom for supporting a load with its center of gravity spaced horizontally outwardly from the mast, counterbalancing arm means fixedly mounted on and extending from said mast section in a direction generally opposite to said load lifting members, and flexible tension means adapted to be operably interconnected with said extending mechanism and said mast section for exerting in tension a load lifting force on said carriage in response to actuation of said extending mechanism to cause vertical load lifting movement of said carriage, support means mounted on said mast section and arm means and training said flexible means thereon such that said flexible means has a first run extending vertically downwardly to a load lifting connection with said carriage and a second run extending vertically downwardly from said arm means at a point spaced horizontally in said opposite direction by a predetermined distance, and connector means for operably connecting said second run to said mast at a support point remote from said assembly at an elevation below said arm means to exert a downward pull via said second run to develop the upward pull in said first run which lifts said carriage, said predetermined distance being correlated with the said load lifting pull in said flexible means such that said second run acting on aid arm means develops a moment acting on said mast section proportional to and oppositely to the load induced moment exerted via said carriage and cantilever support means on said mast section so as to substantially counterbalance load induced bending forces acting on said mast section whereby said bending forces are reacted in said mast section to thereby isolate the upper end of the mast from said bending forces.

9. In a load lifting mechanism for a vehicle the combination comprising an extensible mast including a hydraulic ram and a vertically movable mast section supported by said ram and vertically elevated by actuation of said ram, guide means maintaining said mast section in angular alignment with said ram, load lifting means carried on and vertically movable along said mast section and extending therefrom for supporting a load with its center of gravity spaced horizontally outwardly from said ram, counterbalancing arm means fixedly mounted on and extending from said mast section in the vicinity of the upper end thereof in a direction generally opposite to said load lifting means, and flexible tension means operably interconnecting said ram and mast section for exerting in tension a load lifting force on said load lifting means in response to actuation of said ram to cause vertical load lifting movement of said load lifting means, said flexible means being connected to said counterbalancing arm means and ex-

tending downwardly from said arm means at a point spaced horizontally in said opposite direction by a predetermined distance correlated with the tension force in said flexible means such that said flexible means acting on said arm means develops a moment acting on said mast section proportional to and oppositely to the load induced moment exerted via said load lifting means to thereby substantially counterbalance load induced bending forces acting on said mast, said load lifting means including a carriage having means engaged with said mast section for vertically guiding movement of said carriage on said mast section and cantilever load lifting members carried on said carriage and extending therefrom for supporting a load with its center of gravity spaced horizontally outwardly from said ram, said flexible means operably interconnecting said carriage, ram and mast for lifting said carriage on said mast section in response to expansion of said ram, said flexible means being trained over said counterbalancing arm means and having a first run extending downwardly from said arm means to a load lifting connection with said carriage means and a second run extending downwardly from said arm means at said point such that said second run acting on said counterbalancing arm means develops said counterbalancing moment, said extensible mast further including a second mast section adapted to be supported in fixed position near its lower end on the vehicle, said first and second mast sections each having a pair of horizontally spaced upright rails, said counterbalancing arm means comprising a pair of arms individually cantilever connected to the upper ends of said first section rails and extending generally horizontally therefrom in said opposite direction and being spaced from one another laterally of said mast, said mast further including a pair of orienting arms individually cantilever connected to the upper ends of said second section rails and extending therefrom generally in vertical alignment with said counterbalancing arms, said flexible means comprising a first pair of flexible tension elements disposed one adjacent each side of said mast and each having said first and second runs, first and second rollers rotatably carried on each of said counterbalancing arms respectively supporting said first and second runs of the associated flexible elements vertically above said carriage means and at said point respectively, third and fourth rollers rotatably supported on each of said orienting arms generally vertically aligned with said first and second rollers respectively of the aligned counterbalancing arm, fifth rollers rotatably supported one on each side of one of said ram members near the lower end of said ram, said second runs running vertically downwardly from the associated second rollers to and under the associated third rollers and thence to and over the associated fourth rollers then down and under the associated fifth rollers and thence upwardly to a fixed connection with said fixed mast section.

10. The combination set forth in claim 9 wherein said ram comprises a cylinder member and a plunger member telescopically received in said cylinder member, and wherein said guide means comprises key and keyway means disposed radially intermediate said ram members and extending axially thereof in sliding engagement with at least one of said ram members to prevent relative rotation therebetween and to provide a slide bearing therebetween.

11. The combination set forth in claim 10 wherein said guide means also includes a crosshead secured to the upper end of the uppermost of said ram members, said crosshead having means guidably engaging said mast section.
12. The combination set forth in claim 10 wherein said cylinder member constitutes the lowermost outer part of said ram and said plunger member constitutes the uppermost inner part of said ram.
- 10 13. The combination set forth in claim 12 wherein said ram plunger member has sixth rollers rotatably supported thereon on the upper end thereof and said mast further includes a second pair of flexible tension means individually connected at one end to said rails of said first mast section and running therefrom vertically upwardly to and over the associated sixth rollers and thence downwardly to a connection with said cylinder member.
- 20 14. The combination set forth in claim 13 wherein said first section rails each has an outwardly facing channel and said carriage means comprise first and second pairs of vertically spaced rollers with one pair tracking in each of said channels of said first section rails, and wherein said second section rails each has an inwardly facing channel, said ram having guide rollers carried on said cylinder member and tracking one in each of said channels of said second section rails.
- 25 15. The combination set forth in claim 14 wherein said second mast section has ram guide rollers rotatably supported thereon in rolling engagement with said cylinder member for guiding vertical movement thereof relative to said second mast section.
- 30 16. In an extensible load lifting mast the combination comprising upper and lower vertically overlappable mast sections, a hydraulic ram interposed between said mast sections and including upper and lower relatively movable members, first roller means journaled on said lower ram member, second roller means journaled on said upper ram member, means for guiding vertical movement of said upper mast section relative to said ram and to said lower mast section, load lifting means supported on said upper mast section, first flexible element means connected to said lower mast section and running therefrom under said first roller means then up to a connection with said load lifting means whereby said ram is suspended on said first element means, and second flexible element means connected to said upper mast section and running upwardly over said second roller means and then downwardly to a connection with said lower ram member, said mast sections being vertically separated from one another by extension of said ram, and wherein said guide means comprises antirotation means interengaged between said ram and lower mast section and antirotation means interengaged between said ram and upper mast section, said load lifting means including cantilevered load carrying means movably mounted on and extending outwardly from one side of said upper mast section, said upper mast section having counterbalancing arm means fixedly secured thereto and extending therefrom in a direction generally opposite to said load carrying means, said first flexible element means being connected to said counterbalancing arm means at a point thereon spaced outwardly from said ram and extending downwardly therefrom to exert a downward force on said arm means at said point proportioned to the load lifting force transmitted via said flexible element means.
- 40
- 45
- 50
- 55
- 60
- 65

17. A vertically extensible load lifting mast for a lift truck including in combination first, second, third and fourth mast sections each having a pair of horizontally spaced upright rails successively telescopically interengaged for supporting said mast against bending stresses, said first section constituting the lowermost fixed section of said mast adapted for attachment to the lift truck, said fourth section constituting the uppermost section of the mast, a load lifting carriage having roller means tracking in said rails of said fourth section supporting said carriage for vertical movement along the front of said mast, a hydraulic ram disposed between and generally parallel to said rails and comprising an external cylinder and a plunger telescopically received therein and extending from the upper end thereof, a pair of first rollers rotatably mounted on said cylinder near the lower end thereof, a pair of second rollers rotatably mounted on said fourth mast section near the upper end thereof, a first pair of chains each connected at one end thereof to said first mast section and at the other end thereof to said carriage, said chains being trained around said first and second rollers intermediate said ends thereof whereby said ram is suspended on said first chains, a third set of rollers rotatably mounted on said plunger near the upper end thereof, a second pair of chains each connected at one end to said carriage and at the other end to said cylinder and being trained over said third rollers intermediate said ends thereof whereby said fourth mast section is suspended on said second chains, means directly interconnecting said plunger with said third mast section and means directly interconnecting said cylinder with said second mast section.

18. The combination set forth in claim 7 wherein said connector means comprises a rigid frame connected to said lowermost section of said mast at a point spaced vertically above the lower end thereof, said frame being adapted to be connected to said truck at a point spaced from said mast in said opposite direction, said frame extending in said opposite direction a distance greater than the extent of said counterbalance arms and adapted to extend over an operator station on the truck at an elevation adapted to provide operator clearance thereunder and being constructed to serve as an overhead guard therefor.

19. The load lifting mechanism as set forth in claim 1 wherein said ram comprises a cylinder and a plunger telescopically received in said cylinder, said connector means comprising bracing means mounted on said cylinder and extending generally rearwardly therefrom, said guide means including a crosshead bracket mounted on the upper end of said plunger, second counterbalancing arm means mounted on said crosshead and extending therefrom above and generally in vertical alignment with said bracing means, said mast section being mounted for vertically guided movement on said crosshead, said first-mentioned counterbalancing arm means extending from said mast section above and generally in vertical alignment with said second counterbalancing arm means, first roller means mounted on said plunger near the upper end

thereof, second roller means mounted on said second counterbalancing arm means spaced from said first roller means, said flexible element means further comprising chain means associated with said second counterbalancing arm means and connected at one end to said mast section and at the other end to said bracing means and being trained intermediate said ends over said roller means, said second run being connected to said second counterbalancing arm means whereby said connector means comprises said bracing means, said chain means and said second arm means.

5 20. The combination set forth in claim 19 wherein said second roller means is located between said crosshead and the connection of said second run to said second arm means, said second support means being generally vertically aligned above the connection of said second run to said second arm means.

15 21. The combination set forth in claim 20 wherein said mast section has a pair of horizontally spaced upright rails each having a channel facing inwardly toward the channel of the other rail and said ram is disposed between said channels, and wherein said crosshead has a pair of vertically spaced rollers on each side thereof tracking in said channel of the adjacent one of said rails.

25 22. The load lifting mechanism as set forth in claim 1 wherein said ram includes a cylinder and a plunger telescopically received therein and extending from the upper end thereof, said mast section being mounted on said plunger for movement therewith, said mast section including a pair of horizontally spaced upright rails each having a channel, said ram being disposed between and extending parallel to said rails, said guide means comprising a pair of guide rollers mounted on said cylinder with one of said rollers tracking in each of said channels, said counterbalancing arm means comprising a pair of counterbalancing arms mounted on said mast section and extending therefrom in said opposite direction, said first and second support means comprising respectively a pair of first rollers mounted on said mast section generally above the path of travel of said carriage and a pair of second rollers individually mounted on said arms spaced from said first rollers, said flexible element means comprising a pair of chains one associated with each of said arms each connected at one end to said carriage and extending upwardly therefrom and thus defining said first run and thence over the associated first roller and thence to the associated second roller and thence downwardly to the other end of said chain and thus defining said second run, said connector means operably connecting the other end of each of said chains in fixed relation to said ram cylinder.

30 23. The combination set forth in claim 22 wherein each of said rails of said mast section have an outwardly facing channel, and further including first and second sets of vertically spaced rollers mounted on said carriage and disposed with one set in tracking relation in each of said outwardly facing channels, and wherein said first-mentioned channels constitute inwardly facing channels.
